UNITED STATES PATENT OFFICE.

LOUIS E. BEERS, OF WILKINSBURG, PENNSYLVANIA.

ICE-RUT REMOVER FOR VEHICLES.

1,419,350.

Specification of Letters Patent. Patented June 13, 1922.

Application filed April 17, 1920. Serial No. 374,556.

To all whom it may concern:

Be it known that I, LOUIS E. BEERS, a citizen of the United States, and residing in the borough of Wilkinsburg, in the county of 5 Allegheny and State of Pennsylvania, have invented or discovered new, useful, and Improved Ice-Rut Removers for Vehicles, of which the following is a specification.

My invention consists in a new and improved device to be applied to the wheels of 10 vehicles for the purpose of clearing the streets and highways from ice.

During cold winter weather the roadways 15 tend to become thickly incrusted with ice, frequently the result of the partial melting and subsequent freezing of the snow fall, and in this ice deep ruts are formed which are very destructive to tires and from which vehicles can turn out only with the greatest 20 difficulty. Also, vehicles crossing the ruts at an angle, as at cross streets, are subjected to rough treatment, breaking springs etc. Such conditions frequently last for months, 25 greatly impeding traffic, and causing great damage to power driven vehicles.

The object I have in view is the provision 30 of inexpensive, yet positively and automatically acting means for cutting away the ice crust by enlarging, or shaving down the walls of, the ruts.

For this purpose, I attach to the outer face 35 of the vehicle wheels a metal disk with a relatively sharp perimeter but of somewhat less diameter than the effectual diameter of the wheel, said disk being spaced away from the surface of the wheel. Thus, as the wheels revolve while traveling in the ice ruts, said disks will be continually shaving off the ice at the side of the ruts, thus enlarging and 40 widening the ruts and breaking the ice up into small, loose particles. The result is that the ruts are rapidly widened until in a relatively short space of time the roadway will be substantially cleared.

45 For the sake of convenience I make the disks quickly attachable and detachable, so that the disks may be quickly put on when needed and then, when their use is no longer required, removed. Thus, the disks could be 50 kept on hand by the street department of a municipality, and issued to truck owners when the streets become icy and rutted.

Other novel features of construction and arrangements of parts will appear from the 55 following description.

In the accompanying drawing, Fig. 1 is a

rear view of a motor vehicle whose driving wheels are supplied with my improved ice cutters; Fig. 2 is an outside view of one of the wheels with the cutter attached; Fig. 3 60 shows the cutter detached; Fig. 4 is an enlarged detail showing the preferred method of attaching the cutter to the wheel and Fig. 5 is a perspective of one of the spacer blocks 65 which I prefer to use to properly position the disk in relation to the wheel.

The following is a detailed description of 70 my invention, as the same is illustrated in the drawings.

A represents the driving wheels of a vehicle B, the wheels being shown as travelling in ruts 1 of an ice covered roadway. C represents the ice cutters which are shown as metal plates or disks having circular perimeters but of less diameter than the effectual diameter 75 of the wheel. Said disks have central openings 2 of sufficient diameter to permit free access to the hubs of the wheels A when the disks are in place. Said disks are provided with relatively sharp perimetral edges 3, 80 which may best be formed by double beveling the edge of the disks.

The disks are spaced away from the wheels for a considerable distance so as to clear the outside plane of the tires by, say, from two 85 to four inches.

I find it more convenient to attach the disks to the wheel spokes, and provide attachment means which will permit the disks to be quickly put on or taken off, and which 90 will not require holes to be bored in the wheel. Of course any desired method of attachment to the wheels may be used, but I prefer to secure the disks to the spokes.

Thus, I provide the spacer blocks D preferably of wood, one of whose ends is squared to bear solidly against the inner face of the disk C, while its other end is rounded out to fit snugly against the wheel spoke 4. 5 represents stirrup bolts whose loops pass around 95 the spokes and whose threaded ends protrude out through holes 6 in the disk. Nuts 7 are then screwed up on the ends of the bolts against the outer face of the disk. The edges of the blocks D are preferably grooved or 100 hollowed as at 8 to receive the legs of the bolts, thus enabling the bolts to hold the blocks against displacement.

Thus it is evident that the disks may be 110 quickly put on and taken off, and when in place are held rigidly in position.

The disks will, as has already been ex-

plained act to shave and cut away the ice at the sides of the ruts, but will not themselves come into contact with the permanent road surface, being of less diameter than the 5 wheels.

It is evident that my disks will quickly reduce the deep narrow ice ruts now so characteristic of the roadways in winter, and will thus greatly facilitate traffic and materially 10 reduce the repair bills of vehicle owners.

What I desire to claim is:

1. An ice cutter of the character described consisting of a metal plate having a substantially uninterrupted annular cutting edge, 15 and means for mounting said plate on the outside of a vehicle wheel, said plate being of less diameter than the effectual diameter of the wheel to prevent the perimeter of said plate contacting with the permanent road 20 surface, for the purpose described.
2. An ice cutter of the character described consisting of a metal plate having a substantially uninterrupted annular cutting edge, and means for mounting said plate on the 25 outside of a vehicle wheel and spaced away

therefrom, said plate being of less diameter than the effectual diameter of the wheel to prevent the perimeter of said plate contacting with the permanent road surface, for the purpose described.

3. For use in combination with a vehicle wheel, an ice cutter consisting of a metal plate having an annular perimetral substantially uninterrupted cutting edge, and means extending horizontally from said wheel for supporting the said plate in axial alinement with said wheel and spaced outwardly therefrom, substantially as described.

4. For use in combination with a vehicle wheel, an ice cutter consisting of a metal plate having an annular perimetral substantially uninterrupted cutting edge, and horizontally disposed supporting members extending from the wheel and to the outer ends of which said plate is secured in spaced relation to said wheel and in axial alinement therewith.

Signed at Pittsburgh, Pa., this 14th day of April, 1920.

LOUIS E. BEERS.
